UNITED STATES PATENT OFFICE.

WILHELM L. MEINK, DECEASED, LATE OF LANE, SOUTH DAKOTA; BY ALICE J. MEINK, ADMINISTRATRIX, OF LANE, SOUTH DAKOTA.

AUTOMATIC SHOCKER.

Application filed June 16, 1924. Serial No. 720,387.

To all whom it may concern:

Be it known that WILHELM L. MEINK, deceased, late a citizen of the United States, and resident of Lane, in the county of 5 Jerauld and State of South Dakota, did invent new and useful Improvements in Automatic Shockers, of which the following is a specification.

The present invention relates to automatic 10 shockers, and aims to provide a novel and improved mechanism for receiving the sheaves discharged from a reaper or binder and for automatically shocking the sheaves, to eliminate the manual work in gathering 15 the sheaves together and building up the shocks.

Another object is the provision of such a 20 mechanism having novel means for bringing the sheaves to erect position after being discharged from the binding platform of the reaper or binder, and a further object, in 25 this connection, is the provision of novel means for feeding or moving the sheaves to a point where they are gathered to form the shock.

A further object is the provision of a 30 novel shock forming and binding means, whereby the sheaves are gathered together and formed into a compact shock, and are bound together by a cord or twine embracing the shock.

A still further object is the provision of 35 automatic means for completing and binding the shock after a predetermined number of sheaves are gathered together in the shock forming means, so that the shocks will be of uniform size, as well as being completed without manual attention.

It is also an object of the invention to improve 40 the mechanism generally in its construction and details, to enhance the utility and efficiency thereof.

With the foregoing and other objects in 45 view, which will be apparent as the description proceeds, the invention resides in the construction and arrangement of parts as hereinafter described and claimed, it being understood that changes can be made within the scope of what is claimed, without departing from the spirit of the invention.

The invention is illustrated in the accompanying drawings, wherein—

Figure 1 is a plan view of the automatic shoker, portions being shown in section.

Fig. 2 is a side elevation of the shoker.

Fig. 3 is a fragmentary plan view, portions being shown in section, and showing the parts in a different position than as shown in Fig. 1.

Fig. 4 is a fragmentary plan view of the 60 actuating means.

Fig. 5 is a rear view of the shoker as attached to a binder.

In carrying out the invention the shoker is attached to the reaper or binder at the 65 discharge side thereof, and comprises a platform 11 rigidly secured to the frame 12 of the binder below the delivery edge of the binding platform 13 of the binder. Said platform 11 is spaced sufficiently above the 70 ground to be kept out of contact therewith. The sheaves, when bound on the platform 13 and discharged, fall from the edge of the platform in horizontal position longitudinally of the machine, with their butts for- 75 ward, as usual.

The shoker has means for arighting the sheaves on the platform 11 and feeding or moving the sheaves to the shock forming means (described in detail hereinafter). 80 Thus, a cone 14 is mounted for rotation above the platform 11 beyond the discharge or delivery edge of the platform 13, and is secured on a vertical shaft 15 journaled in the platform 11. Said cone 14 has a plu- 85 rality of sets of vertically spaced arms 16 for catching the sheaves and moving same outwardly away from the platform 13 and rearwardly, as will hereinafter more fully appear. 90

The sheaves are guided rearwardly from the cone 14 to the shock forming means in a passage-way defined between the outer and inner vertically spaced guide rods 17 and 18, respectively. The rods 17 are curved in- 95 wardly at their forward terminals toward the forward edge of the platform 13, and their forward ends are secured to a post 19 carried by the platform 11 in front of the cone 14. The rear ends of the rods 17 and 18 are secured to posts 20 and 21, respectively, carried by the platform 11 at the rear end thereof. The rod 18 is formed with a bearing 22 receiving the upper ter- 100 minal of the shaft 15, and said rod 18 has a brace 23 extending from the shaft 15 to the platform 13 and secured, as at 24, to said platform. The brace or portion 23 assists in steadyng the shaft 15 and cone 14, and also provides a support or rest for the head 105 110

of the sheaf which is discharged from the platform 13. Thus, when the sheaf rolls from the platform 13, the head thereof rolls over onto the portion 23 of the rod 18, while the butt end of the sheaf can drop down on the platform. This will bring the sheaf to a rearwardly inclined position, so as to partly bring the sheaf to upright position. The cone 14 rotates clock-wise, as seen in Fig. 1, so that the arms 16 move forwardly adjacent to the platform 13, to catch the sheaf and carry it outwardly in front of the cone and then rearwardly. The sheaf being taken hold of and moved with the arms 16 will be brought to an upright position between the rods 17 and 18.

Spring guide rods 25 are secured to the post 19 and extend outwardly and rearwardly along a curve line inwardly of the rods 17, and said rods 25 have the coils or loops 26, whereby the rods 25 can spring outwardly away from the cone 14. The rods 25 are arranged to guide the sheaves as they are moved outwardly and rearwardly with the cone, said rods being yieldable and hold the sheaves against the cone under slight pressure, to prevent the sheaves being thrown away from the cone.

From the cone 14 the sheaves are fed or delivered rearwardly between the posts 20 and 21 to the shock forming means, and an oscillatory feeder 27 is provided, which constitutes a lever and which has upper and lower prongs or tines to engage the sheaves. The feeder or feeding lever 27 has its inner end pivoted to a link 28 which is in turn pivoted to a bracket 29 secured to the post 21, thereby fulcruming the feeder for oscillatory and longitudinal movements to the frame of the shucker. The feeder 27 is connected between its ends with an upstanding crank 30 carried by the shaft 31 journaled in the platform 11, in order to give the feeder a forward and rearward oscillatory motion combined with an inward and outward movement. The shaft 31 and crank 30 rotate clock-wise as seen in Fig. 1, similar to the cone 14, and the feeder 27 is retracted in its rearmost position from the sheaf passage-way between the rods 17 and 18, and then, in succession, is moved forwardly, projected outwardly to said passage-way across the sheaf, and moved rearwardly to move the sheaf rearwardly with it between the posts 20 and 21. In other words, starting with the feeder 27 in the position shown in Fig. 1, as the crank 30 continues to turn clock-wise, the crank 30 will move the feeder 27 inwardly, thereby retracting the feeder from the passage-way between the guide rods 17 and 18, the link 28 permitting the feeder to be moved longitudinally of itself inwardly. Then, the crank 30 moves forwardly, thereby swinging the feeder 27 forwardly, as

seen in Fig. 3, and the crank 30 then moves outwardly so as to move the feeder 27 outwardly in front of a sheaf that has been delivered between the rods 17 and 18 by the cone 14. The crank 30 then moves rearwardly, so as to swing the feeder 27 rearwardly to the position shown in Fig. 1, causing the sheaf to move with the feeder and to be delivered rearwardly between the posts 20 and 21, thus completing the cycle of movements of the feeder. Thus, the feeder is retracted when moved forwardly and is projected to engage and move the sheaf when the feeder is moved rearwardly.

The shafts 15 and 31 are operated from the operating mechanism of the binder. Thus, a bevel gear wheel 32 is secured on the shaft 31 within the platform 11 (the platform being hollow), and a bevel pinion 33 meshes with the gear wheel 32 and is secured on a shaft 34 journaled in bearings within the platform. Said shaft 31 is connected by a sprocket chain 35 with a shaft 36 of the binder, so that the shaft 31 is driven from the binder. The shafts 15 and 31 are connected by a sprocket chain 37 passing around sprocket wheels 38 and 39 secured on the shafts 31 and 15, respectively, within the platform. The sprocket wheel 39 is of larger diameter than the sprocket wheel 38, whereby the feeder 27 makes a complete cycle of movement for each step of rotation of the cone 14, or for each set of arms 16. As shown, with three sets of arms 16, the feeder 27 makes three complete cycles of movements for each revolution of the cone 14.

A dog is provided for holding the sheaves against forward movement after being moved rearwardly between the posts 20 and 21 by the feeder 27. As shown, said dog comprises the vertically spaced arms 40 secured to a vertical shaft 41 journaled in the platform 11 and to a post 42 secured on the platform. Said post 42 can also serve as a support for the rods 17. The arms 40 have outwardly extending portions 43 slidable through the post 20 and curved about the shaft 41, as a center, thereby steadyng the movement of the arms or dog 40. Springs 44 connect the post 20 and outer terminals of the portions 43 to move the arms or dog 40 inwardly to closed position. When a sheaf is carried by the feeder 27 rearwardly past the dog 40, said dog is forced outwardly by the sheaf, and when the sheaf is moved between the posts 20 and 21 beyond the dog, the springs 44 swing the dog inwardly in front of the sheaf, whereby the portions 43 prevent the sheaf from moving forwardly, thereby locking the sheaf in the shock forming means.

The shock forming means includes a shock supporting and dumping platform 45 which is hinged, as at 46, to the rear end of

the platform 11 so as to swing downwardly and upwardly from and to horizontal position, as seen in Fig. 2. As shown, the platform 45 has prongs or teeth 47 extending from the rear edge thereof to facilitate the dumping of the shock from the platform when the platform swings downwardly. The prongs or teeth 47 also enable the platform 45 to move over the stubble, by leaving a clearance between the rear edge of the platform and the ground, even though the teeth or prongs 47 extend to the ground.

10 The shock forming means further includes vertically spaced arms 48 secured to vertical shafts 51 journaled in bearings carried by the posts 20 and 21 for compressing the shock, by holding the sheaves together as they are gathered to form the shock. The shafts 51 have arms 49 sufficiently high up to be disposed above the sheaves, and a spring 50 connects the arms 49, to swing the arms 49 toward one another, and thereby swing the arms 48 toward one another across the space between the posts 20 and 21, as seen in Fig. 3, when the shock has been discharged. As the sheaves are delivered rearwardly between the posts 20 and 21, which define the throat of the shock forming means, the arms 48 are swung rearwardly and outwardly away from one another, thereby stretching the spring 50, and the rearward and outward motion of the arms 48 is resisted by said spring, so that the sheaves which are moved between said arms are held together under spring pressure.

15 The means for raising and lowering the platform 45 includes a spring 52 connected to an upstanding arm 53 secured to the platform 45 and to an upstanding bracket 54 secured on the platform 11, said spring raising the platform 45 and holding it in position to support the shock. A link 55 is connected to the arm 53 and to an upstanding portion 56 of a lever 57 fulcrumed in the platform 11, whereby the lever 57 in being swung to shove the link 55 rearwardly, will swing the arm 53 rearwardly to swing the platform 45 downwardly to dumping position. The top of the platform 11 has a slot 58 in which the portion 56 moves.

20 Means is provided for binding the shock with cord or twine, and includes a needle 60 slideable transversely in a bracket 61 carried by the post 21, whereby the needle can be projected across and retracted from the throat of the shock forming means or rear end of the passage-way between the guide rods 17 and 18. The cord or twine 62 passes through the eye of the needle and around the sheaves on the platform 45, said cord being unwound from a spool 63 carried by the bracket 61 or other suitable support. The needle 60 is retracted by a coiled spring 64 surrounding the needle and con-

fined between the bracket 61 and the inner end of the needle. The needle has rack teeth 65 meshing with a pinion 66 secured on a vertical shaft 67 journaled in the platform 11 and bracket 61, whereby the needle 70 is projected when the shaft 67 is rotated in the proper direction.

25 A knitter 68 of any suitable or well known kind is carried by the post 20 to receive the needle 60, when projected, for 75 tying the cord around the shock and cutting the cord. The details of the knitter are omitted, inasmuch as any well known knitter mechanism can be used. When the band is tied around the shock, the band is released, 80 and the terminal of the cord is held in the knitter while the needle is retracted, so that the cord extends across the throat of the shock forming means, resulting in the cord being forced rearwardly by the sheaves to 85 form a loop extending around the sheaves from the knitter to the needle, said needle being normally retracted, as seen in Fig. 3, during the formation of the shock. The knitter 68 is operated by a vertical shaft 69 90 journaled in the platform 11.

30 The mechanism includes automatic actuating means for the needle, knitter and platform 45, so that the shock is automatically bound and discharged. Such actuating means includes a master wheel 70 mounted for rotation in the platform 11 and having the gear teeth 71 to engage and rotate in succession the pinions 72 and 73 which are operatively connected with the 100 respective shafts 67 and 69. The wheel 70 also carries a tappet pin 74 to contact with and swing the lever 57 after the gear teeth 71 have turned or rotated the pinion 73. Thus, when the wheel 70 is rotated 105 (counter-clock-wise as seen in Fig. 4) the teeth 71 first rotate the pinion 72 to project the needle 60 into the knitter 68; the teeth 71 then rotate the pinion 73 to operate the knitter 68; and the pin 74 then swings the lever 57 to depress the platform 45. Thus, the loop of the cord or twine 62 which extends around the shock is closed within the knitter and the cord tied to form the band embracing the shock, and the shock is then 110 dumped from the platform 45 onto the ground by the downward swinging movement of said platform.

35 The actuating means for the needle, knitter and platform 45 is automatically controlled so that the shock is bound and discharged when a predetermined number of sheaves are delivered into the shock forming means. Thus, the oscillation of the dog 40 is used for determining the number of 120 sheaves that are required to complete the shock. A clutch member 75 is connected to a bevel pinion 76 engaging the gear wheel 32, so that said clutch member 75 is rotated 125 during the operation of the shocker. A com-

panion clutch member 77 is slidable into and out of engagement with the clutch member 75, and is connected by bevel gear wheels 78 with the master wheel 70, so that said master wheel is rotated when the clutch is closed. The clutch member 77 is shifted by a lever 79. A cam wheel 80 is mounted for rotation in the platform 11 and has the cams 81 for swinging a lever 82, which is fulcrumed at 83 within the platform 11, and a link 84 connects the levers 79 and 82. When a cam 81 passes the lever 82, said lever 82 is swung to swing the lever 79 so as to close the clutch. The lever 82, when the clutch is closed, extends across the path of movement of the pin 74, so that when the wheel 70 completes one revolution, the pin 74 will contact with and swing the lever 82, to open the clutch, thereby stopping the wheel 70. The cam wheel 80 is turned step by step as the sheaves are delivered into the shock forming means. Thus, an arm 86 is secured to the shaft 41 within the platform 11 and has a pawl 85 pivoted thereto which engages a ratchet wheel 85 secured to the wheel 80. As shown, the ratchet wheel 85 has seven teeth for each cam 81, so that the shock is composed of seven sheaves, although more or less ratchet teeth can be used when the shocks are to contain more or less numbers of sheaves.

The operation of the shocker is as follows: With the shock forming means empty, as seen in Fig. 3, the arms 48 are swung forwardly across the throat of said shock forming means, and the needle 60 is retracted with the end of the cord 62 held in the knotter 68. The cord extends across the throat of the shock forming means from the knotter 68 to the needle 60. The platform 45 is held in raised position by the spring 52. Now, as the sheaves drop from the platform 13, their butt ends fall on the platform 11, while the heads of the sheaves are supported by the portion 23, and the sheaves are immediately taken by the arms 16 and moved to upright position between the guide rods 17 and 18, assisted by the guide rods 25. As soon as a sheaf is delivered by the arms 16 between the rods 17 and 18, as seen in Fig. 3, the feeder 27 moves outwardly in front of the sheaf and then rearwardly, to move the sheaf rearwardly past the dog 40 and into the shock forming means. The sheaves are thus fed one at a time into the shock forming means, and each time a sheaf is moved into the shock forming means, the dog 40 is swung outwardly and then inwardly, to hold the sheaf in the shock forming means. Each time the dog 40 is oscillated, the pawl 85 advances the ratchet wheel 85 and cam wheel 80 one step. The cord 62 is forced rearwardly between the posts 20 and 21 by the sheaves so that the cord is formed into a loop surrounding the

sheaves on the platform 45, and the sheaves also force the arms 48 rearwardly and outwardly, as the sheaves are gathered on said platform 45. The arms 48 being under spring influence, have a tendency to swing toward one another, thereby pressing the sheaves together. The shock is thus built up as the sheaves are gathered on the platform 45 between the arms 48 and within the loop of the cord 62.

When the predetermined number of sheaves are delivered into the shock forming means (seven as shown) the dog 40 having been oscillated seven times, will have advanced the ratchet wheel 85 and cam wheel 80 seven steps, so that the cam 81 swings the lever 82 to close the clutch, and the clutch member 77 being engaged with the clutch member 75, will result in the master wheel 70 being rotated from the operating means. The gear teeth 71 will first turn the pinion 72 and will then turn the pinion 73, so that the needle 60 is projected into the knotter 68 and the knotter operated to tie the band around the shock in the usual manner. The pin 74 then swings the lever 57 to depress the platform 45 and discharge the shock onto the ground. The wheel 70 continues its movement and the pin 74 then swings the lever 82 so as to open the clutch, when the revolution of the wheel 70 has been completed, it being noted that when the lever 82 is swung by a cam 81 to close the clutch, said lever projects into the path of the pin 74. As soon as the teeth 71 leave the pinions 72 and 73, the needle 60 is retracted by the spring 64, and the operation of the knotter 68 is stopped, and when the pin 74 leaves the lever 57, the spring 52 again raises the platform 45, so that the mechanism is again ready for the formation of the next shock. The arms 48 are also swung forwardly, as seen in Fig. 3, as soon as the shock is discharged from the platform 45 from between said arms 48.

Having thus described the invention, what is claimed as new is:—

1. A shocker attachment for a reaper or binder comprising a platform for receiving the sheaves from the reaper or binder, shock forming means, and means for feeding the sheaves to said means including a cone rotatable above the platform and having outstanding arms for catching the sheaves as they fall from the reaper or binder and for moving the sheaves to upright position.

2. A shocker attachment for a reaper or binder comprising a platform to receive the sheaves from the reaper or binder, shock forming means, guiding means in which the sheaves are movable to the shock forming means, and means for feeding the shocks along said guiding means into the shock forming means including a cone rotatable on the platform and having outstanding

arms for catching the sheaves as they drop from the reaper or binder and for moving said sheaves into the guiding means in upright position.

- 5 3. A shocker attachment for a reaper or binder comprising a platform to receive the sheaves from a reaper or binder, shock forming means, a cone rotatable on the platform and having outstanding arms for catching the sheaves as they are delivered from the reaper or binder and for moving the sheaves to upright position, and a feeder operable for moving the sheaves from said cone into said means.
- 10 4. A shocker attachment for a reaper or binder comprising a platform, shock forming means, a rotatable member on the platform having outstanding arms for catching the sheaves delivered from the reaper or binder and moving them to a position on the platform, a feeder mounted above the platform for moving the sheaves from said position into said means, and actuating means for said member and feeder including a crank connected to said feeder to oscillate the feeder between said member and means and to project and retract the feeder adjacent to said member and means, respectively.
- 15 5. A shocker attachment for a reaper or binder comprising a platform for receiving the sheaves from the reaper or binder, shock forming means, guiding means for the movement of the sheaves to said shock forming means, a rotatable member on the platform having outstanding arms for catching the sheaves as they are delivered from the reaper or binder and for moving the sheaves into the guiding means in upright position, a feeder mounted above the platform for oscillatory and longitudinal movements, and actuating means for said member and feeder including a crank connected to said feeder to oscillate the feeder between said member and shock forming means and to project and retract said feeder relatively to the guiding means adjacent to said member and shock forming means, respectively, so that said feeder moves the sheaves in the guiding means into the shock forming means.
- 20 6. A shocker comprising shock forming means, a passage way leading to said

means, means for feeding sheaves in said passage way into said means, means in said passage way for retaining the sheaves in said shock forming means and movable out of the way by the sheaves when they are fed into said shock forming means, and automatic means for binding the shock in the shock forming means when said retaining means has been moved a predetermined number of times by the sheaves passing it.

25 7. A shocker comprising shock forming means, a passage way leading to said means, means for feeding sheaves in said passage way into said means, a dog in said passage way for retaining the sheaves in said means and movable out of the way by the sheaves when moved past said dog, and automatic means for binding the shock in said means when said dog has been moved a predetermined number of times by the sheaves passing it.

30 8. A shocker comprising a platform, a shock supporting platform hingedly connected to the first named platform, a passage way for the sheaves above the first named platform leading to the shock supporting platform, means for feeding the sheaves in said passage way onto the shock supporting platform, spring influenced arms supported at opposite sides of said passage way above the shock supporting platform to swing toward one another so as to hold the sheaves together on the shock supporting platform, a reciprocatory needle supported at one side of the passage way to be projected across the passage way and through which a cord extends to pass around the sheaves on the shock supporting platform, a knotter supported at the opposite side of the passage way for holding the end of the cord and for receiving the needle to tie the cord around the shock, and actuating means operable for projecting the needle into the knotter, for operating the knotter and for swinging the shock supporting platform downwardly to dumping position.

35 In testimony whereof I hereunto affix my signature.

ALICE J. MEINK,
Administratrix of the Estate
of W. L. Meink, deceased.
